[57] **CLAIM**

The ornamental design for a catheter field trimming device, as shown and described.

DESCRIPTION

FIG. 1 is a front perspective view of the catheter field trimming device of the present invention showing my new design; and

FIG. 2 is a front elevational view thereof, the rear view being a mirror image;

FIG. 3 is a top plan view thereof;

FIG. 4 is a bottom plan view thereof; and,

FIG. 5 is a side view thereof, the other side being a mirror image.
